UNITED STATES PATENT OFFICE

CHARLES HARRIS COOK, OF HUGO, COLORADO

ROAD DRAG

Application filed June 26, 1930. Serial No. 464,029.

This invention relates to an improved attachment for a road drag, wherein the attachment has the function of a dirt spreader.

More specifically, the inventive novelty is predicated upon an attachment characterized by a yoke fastened to the rear end of the main frame and provided with a horizontally disposed levelling and spreading blade, swingably mounted on a vertical axis, means being provided for adjusting the blade to the desired angle with respect to the longitudinal axis of the line of draft.

In the drawings:

Figure 1 is a top plan view of a road drag embodying the improvements of this invention.

Figure 2 is a side elevational view thereof.

Figure 3 is a transverse vertical sectional view taken through the fulcrum bar and the link and showing the levelling blade and the support in elevation.

Referring now to the drawings, by reference numerals, it will be seen in Figure 1, that the character 4 designates generally a conventional road drag frame, embodying side bars 5, intersecting cross braces 6, and a horizontal frontal plate 7. The numeral 8 designates generally the supporting wheel structure, which renders the device portable.

30 The improved attachment comprises a yoke 11, fastened to the rear end portions of the side bars 5, and provided with a central extension 12, projecting rearwardly from the crown portion thereof, to form a fulcrum.

35 Mounted at a point between its ends on this bar is the spreading and levelling blade structure generally represented by the numerals 13. This comprises a carrier plate 14, and a blade 15, of appropriate design fastened thereto. There is a rib 16 formed across

40 the carrier plate 14, and this is provided with a central lug 17, having pivotal connection as at 18, to the adjacent fulcrum bar 12. A suitable bracket 19 is attached to the rib on one

45 side of the pivotal connection, and a push pull rod 20 is pivotally connected at one end with the bracket and has its forward end pivotally connected with the lower end of the operating lever 21. This lever is pivotally mounted on

50 the front plate 7, provided with the pawl

structure, cooperable with the rack segment 22. This arrangement permits the spreader 13 to be rocked about its pivot on a vertical axis to the dotted line positions represented in Figure 1, thereby permitting the dirt to cast either to the left or right, according to the condition of the road. The gist of the construction is in the provision of an attaching yoke, having a central rearwardly extending fulcrum bar, together with the combined spreader and levelling device 13, pivotally connected to the bar on a vertical axis, this device 13 being of a width approximately equal to that of the frame 4, so as to occupy a swingable and adjustable position between the main drag blades of the device which are not shown. The inventive novelty is founded on the attachment per se as well as in the combination to the existing features of the standard road drag structure herein illustrated.

Various changes in the shape, size and arrangement of parts may be resorted to, without departing from the spirit of the invention or the scope of the appended claims. 75

Having thus described my invention, what is claimed is:

1. In a structure of the class described, in combination, a portable frame including a pair of spaced substantially parallel side bars, 80 a front plate attached to the corresponding ends of said side bars, a yoke having its end portions fastened to the rear end portions of the side bars, said yoke being provided with a central rearwardly projecting bar extension, and a combined levelling and spreading blade device fulcrumed on said bar.

2. In a structure of the class described, in combination, a main supporting frame embodying a pair of spaced side bars, a horizontal plate fastened across the forward end portions thereof, a substantially U-shaped yoke having its end portions attached to the rear end portions of said side bars, and formed with a central rearwardly projecting extension bar, a plate embodying a lug pivotally mounted on said bar, a spreader blade carried by said plate.

3. In a structure of the class described, in combination, a main supporting frame em- 100

bodying a pair of spaced side bars, a horizontal plate fastened across the forward end portions thereof, a substantially U-shaped yoke having its end portions attached to the rear 5 end portions of said side bars, and formed with a central rearwardly projecting extension bar, a plate embodying a lug pivotally mounted on said bar, a spreader blade carried by said plate, a link pivotally connected at its 10 rear end to said plate, on one side of the pivotal mounting of the plate, said link extending forwardly over the frame structure, a lever pivotally mounted on said front plate, a segment carried by said plate, and a pawl 15 carried by said lever cooperable with said segment.

4. An attachment of the class described, comprising a yoke a supporting frame with which the yoke is connected, a centrally disposed bar member projecting from the crown portion of the yoke, a carrier blade provided with a lug resting on the adjacent end of said extension, a vertical pivot pin pivotally assembling said carrier plate on said extension, 25 a combined drag and levelling blade carried by said plate, a bracket on the carrier plate located on one side of the lug, and an operating link connected with said bracket.

In testimony whereof I affix my signature.
36 CHARLES HARRIS COOK.
